(57) **CLAIM**

I claim the ornamental design for a guitar string wrap, as shown and described.

DESCRIPTION

FIG. 1 is a top perspective view of a guitar string wrap showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a perspective view thereof, the guitar string wrap shown attached to a guitar.

The broken lines in FIGS. 1-7 represent the portions of the guitar string wrap that form no part of the claimed design. In FIGS. 1, 2, and 7, the dotted lines represent a hook-and-loop material, which forms no part of the claimed design. The broken lines in FIG. 8 showing a guitar are for the purpose of illustrating environmental structure only and form no part of the claimed design.
